(57) **CLAIM**

The ornamental design for a conduit coupler, as shown and described.

DESCRIPTION

FIG. 1 is a perspective view of a first embodiment of a conduit coupler showing our new design;

FIG. 2 is a front elevation view thereof, the back elevation view and side elevation views being identical thereto;

FIG. 3 is top plan view thereof, the bottom plan view being identical thereto;

FIG. 4 is a perspective view of a second embodiment of a conduit coupler showing our new design;

FIG. 5 is a front elevation view thereof, the back elevation being identical;

FIG. 6 is a side elevation view thereof, the reverse side elevation view being identical;

FIG. 7 is top plan view thereof, the bottom plan view being identical thereto;

FIG. 8 is a perspective view of a third embodiment of a conduit coupler showing our new design;

FIG. 9 is a side elevation view thereof, the reverse side elevation view being identical;

FIG. 10 is a front elevation view thereof, the back elevation view being identical; and,

FIG. 11 is top plan view thereof, the bottom plan view being identical thereto.

The portion of the conduit coupler depicted in broken lines forms no part of the claimed design.

1 Claim, 11 Drawing Sheets
